UNITED STATES PATENT OFFICE.

CHARLES S. EVANS, OF OAKLAND, CALIFORNIA, ASSIGNOR TO THE PARAFFINE COMPANIES, INC., OF SAN FRANCISCO, CALIFORNIA, A CORPORATION OF DELAWARE.

PIPE-WRAPPING MACHINE.

Application filed May 11, 1926. Serial No. 108,240.

My invention relates to machines for winding strips of covering material upon cylindrical or other bodies and especially to pipe wrapping machines.

5 One of the objects of the invention is the provision of a pipe wrapping machine which may readily be set up and operated in the field where the pipe is to be used.

Another object of the invention is the provision of a pipe wrapping machine of simple and rugged construction and one particularly suitable for wrapping heavy pipe of large diameter.

Another object of the invention is the provision of a pipe wrapping machine in which the pipe is propelled forward by movement of a carriage on which the end of the pipe is supported, the carriage also embodying means for rotating the pipe and means for 20 adjusting to a predetermined ratio the rotary speed of the pipe and the forward speed of the carriage.

Another object of the invention is the provision of a pipe wrapping machine of the character described embodying automatically operating means for stopping at predetermined points the dual movement of the pipe.

My invention possesses other objects and features of advantage, some of which with the foregoing will be set forth in the following description of my invention which is illustrated in the drawings forming part of the specification. It is to be understood that I do not limit myself to the showing made by the said description and drawings, as I may adopt varying forms of my invention within the scope of the claims.

Referring to the drawings:

40 Figure 1 is divided into two parts, 1^a and 1^b, and shows a plan view of the complete machine with two lengths of pipe therein. Figure 1^a is a plan of that portion of the machine including the carriage and track, a portion being broken away to shorten this part of the figure. Figure 1^b is a plan view of that part of the machine including the mechanism for feeding a strip of wrapping material to the pipe, the means for applying the saturant material to the strip, and the supporting means for the pipe after it leaves the wrapping mechanism.

Figure 2 is a vertical sectional view thru a portion of the driving mechanism, the plan of section being indicated by the line

2-2 of Figure 1^a. Figure 3 is a plan view of the cam for automatically controlling the carriage. Figure 4 is an elevation of the friction clutch and operating means. Figure 5 is an end elevation of the chuck. Figure 6 is an end elevation showing the means for supporting the pipe. The direction of the view is indicated by the arrow 6 of Figure 1^b.

In terms of broad inclusion my invention 65 comprises a machine for winding upon a pipe or other object to be wrapped, a strip of material saturated and/or coated with a suitable waterproof and decay-proof material, preferably of bituminous character, 70 thus giving the pipe a protective sheathing of great durability. The end of the strip which passes thru the saturant material before it reaches the pipe is applied at an angle to the pipe, and the pipe is then turned 75 and at the same time fed forwardly so that the wrapping strip is drawn thru the coating material and upon the pipe to form a helical wrapping thereon.

The pipe is supported at one end on the carriage and at the forward or leading end on suitable casters. Means are provided for propelling the carriage forwardly and at the same time rotating the pipe-supporting-head and these two movements, that is, axial and rotary are so proportioned that the resultant movement of the pipe will draw the wrapping material thereon in a helix, the pitch of which is determined by the ratio between these two speeds. This ratio is adjusted in accordance with the width of the wrapping strip, the size of the pipe and whether the wrapping strip is to be applied with flush joints or lap joints.

A prime mover of any suitable type, conveniently an electric motor, is arranged upon the carriage and connected by suitable gearing to a bull wheel meshing with the stationary rack so that rotation of the bull wheel propels the carriage along the track. Transmission mechanism embodying a speed varying device also connects the prime mover with the pipe-supporting-head or face plate, so that the speed of rotation of the face plate may be proportioned to the driving speed of the carriage. Friction clutch means are interposed between the prime mover and the driving mechanism and both manual and automatic means are provided for controlling this clutch so that the carriage feed as

well as the rotation of the face plate may be automatically controlled. Clutch means are also provided in the driving mechanism for reversing the direction of rotation of the 5 bull wheel to return the carriage to first position at a higher rate of speed than its forward movement, and for permitting the carriage and the face plate to be moved independently.

- 10 In terms of greater detail my machine comprises a suitable frame 2 to support the tracks 3, upon which the carriage 4 is adapted to run on the wheels 5. Journaled in the bearing fixed on the carriage is a face plate 6, provided with a chuck having a cone flange 7 adapted to seat in the end of the pipe 8 which is to be wrapped. Two or more toothed dogs 9 are pivotally mounted on the chuck to engage the pipe and insure it turning with the face plate. Each dog is retained by a spring 11 in either active or inactive position as shown in Figure 5. Several different sizes of chucks are provided to fit different sizes of pipe, and are fastened 20 to the face plate by means of cap screws 12. The periphery of the face plate is provided with gear teeth in which mesh the driving pinion 13, journaled on suitable brackets extending from the body of the carriage. 25 The pinion is fixed on the shaft 14 and connected by the gears 16 with the shaft 17, on the other end of which is removably mounted the gear 19 forming one of a set of change-gears including also the gear 21, fixed 30 for rotation with the main transmission shaft 22. A connecting gear 23 is mounted on the arm 24 in the usual way.

Means are provided for driving the main transmission shaft from the motor 26, and 40 for disconnecting the shaft from the motor at predetermined points in the travel of the carriage. Preferably a standard motor of about 1750 R. P. M. is used and it is therefore necessary to cut the speed down. For 45 this purpose I provide a worm gearing 27, between the motor shaft and the shaft 28, and a worm gearing 29 between the shaft 28 and the shaft 31 on which is loosely mounted a sleeve 32 having a gear 33 fixed at one end, 50 and with a friction clutch 34 at the other end interposed between the sleeve and the shaft. The clutch is operated by the collar 36 connected by yoke 37 and rod 38 with the control lever 39, pivoted on the pin 41, by 55 the side of the lever 42, to which it is normally locked by the spring pressed latch 43, released by the grip lever 44. The lower end of the lever 42 is connected to the rod 46 slidable in the bracket 47 and actuated 60 by the roller 48 in the cam groove 49. Thus the cam will automatically operate the clutch, which may also be operated manually by releasing the latch 43.

The gear 33 is in mesh with a wide gear 65 51 loosely mounted on the main shaft 22

and forming part of a clutch having a plurality of teeth 52 on one side and two sets of teeth 53 and 54 on the other side. The clutch gear 51 is provided with an annular groove engaged by the shifting yoke 55, connected by the rod 56 to the control lever 57, held by the latch 58 in one of three positions determined by notches in the segment 59. Also mounted for axial movement on the main shaft, but splined thereto, is a sleeve 70 75 60, having an annular groove engaged by the shifting yoke 61, connected to the control lever 62, held by the latch 63 in one of three positions determined by notches in the segment 64. The sleeve 60 is provided with a plurality of teeth 66 adapted to be engaged with the teeth 54 on the clutch gear. Journaled on the sleeve 60 is the hooded gear 67 having teeth 68 adapted to be engaged with the teeth 53 on the clutch gear. The gear 67 is in mesh with the bull wheel or gear 69 meshing in the rack 71, and fixed on the shaft 72 journaled in suitable bearings below the carriage. A small sprocket 73 is fixed on this shaft and is connected by chain 74 80 85 to the large sprockets 76 fixed on the sleeve 77 which is journaled in the bearing 78 and loose on the main shaft 22. The sleeve is also provided with teeth 79 adapted to interlock with the teeth 52 of the clutch gear. 90 95

From the above it will be clear that with the control lever 62 in central position the clutch gear 51 may be shifted to interlock the teeth 53 and 68, and simultaneously engage the teeth 54 in the teeth 66. When 100 these engagements have occurred it is obvious that the gear 51 is locked for rotation with both the gear 67 and sleeve 60 and therefore with the main transmission shaft, and that the engagement of the friction 105 clutch 34 will result in propelling the carriage forwardly and rotating the face plate and pipe.

If the clutch gear is shifted in the other direction to interlock the teeth 52 and 110 79, the drive thru the sprockets 76 and 73 and shaft 72 to the bull wheel is at higher speed and in the contrary direction to move the carriage backwardly to first position, the main shaft 22 and the face plate drive being 115 inactive during this recovery movement of the carriage, and the gear 67 turning freely on the sleeve 60.

It will also be seen that by appropriate shifting of the clutches, the face plate may 120 be rotated, or the carriage moved, each independently of the other. When the carriage only is to be moved forwardly, the lever 62 is pulled backwardly (to the left of Figure 2) so that the teeth 66 are not engageable by the teeth 54. Movement backwardly of the lever 57 to engage the teeth 53 and 68 results in a forward drive connection for the carriage. 125

If it is desired merely to rotate the pipe 130

without moving the carriage, this may be done by leaving the lever 57 in central position and moving the lever 62 to engage the teeth 66 with the teeth 54. Separate movement of the carriage in either direction or rotation of the face plate, is usually necessary during the positioning of the pipe on the machine and the starting of the wrapping strip.

- 10 As shown in Figure 3, the cam 49 is provided with offset portions 81 and 82, so formed that the friction clutch 34 is disengaged automatically when the carriage reaches either end of the track. Thus at the 15 rear end of the track the carriage is brought automatically to rest and at the forward end of the track the carriage is brought automatically to rest and the rotation of the pipe interrupted simultaneously. It will 20 also be noted that an offset portion 83 is provided in the cam for the purpose of automatically stopping the forward movement of the carriage and the rotation of the pipe at a predetermined point to permit the 25 wrapping to be interrupted over the joint between the two pieces 8 and 8' of the pipe. While permanently joined pipe may be wrapped, the wrapping extending continuously over the coupling, it is usually desirable 30 to leave a space 84 at each end of each piece of pipe free of wrapping to facilitate the joining of the lengths of the pipe when laid. When this system is followed the successive lengths of pipe are joined temporarily 35 by a plug coupling 86 having conical ends 87 adapted to seat in the adjacent ends of the pipe. By reason of the spring held lever 88, which acts as a switch, the offset portion 83 is operative only on the forward 40 travel of the carriage. The cam is straight for the return trip so that the carriage movement is not interrupted before its completion.

45 Fixed at suitable intervals along the frame 2 are caster wheels 93, preferably arranged in groups of three as shown in Figure 6. Each wheel is mounted on a shaft 94 held axially in position by the collars 96 so the 50 caster wheels may be radially adjusted in accordance with the size of pipe being wrapped. The caster mounting of the wheels 93 is of course prompted by the fact that the motion of the pipe is a helical one.

55 Means are also provided for feeding a strip 97 of wrapping material to the pipe and for applying to the strip a cementitious water proof material preferably of a bituminous nature. A well designed and convenient mechanism for doing this is shown 60 in the co-pending application of Leland S. Rosener, Serial Number 728,551 filed July 28, 1924. It is therefore not necessary to describe this mechanism in detail, but in general terms the device comprises a frame

98, mounted for pivotal movement above the 65 vertical axis 99 and disposed over the tank 101, which is adapted to hold the bituminous material thru which the strip of wrapping material is passed by means of the guide and tension rollers 102. The material in the 70 tank is kept in a fluid condition by suitable burners within the flues 103.

The strip of wrapping material is drawn off of the supply roll 104, suitably carried on the frame; and the angular position of 75 the frame, which is of course dependent on the ratio of the two movements of the pipe, is fixed by the arm 106.

In using my machine a piece of pipe is inserted in the machine on the supporting 80 caster wheels 93 with the forward end of the pipe in convenient position opposite the frame holding the wrapping material. The carriage is then run forward to seat the 85 chuck on the face plate in the rear end of the pipe. The strip of wrapping material is then started by hand, and continued by the proper engagement of the clutches. As the carriage reaches the end of its forward 90 movement motion automatically ceases by the disengagement of the friction clutch 34. The chuck dogs are now turned out of engagement with the pipe and the lever 57 pushed in to engage the teeth 52 and 79. With the throwing in of the friction clutch 95 34, the carriage is backed free of the pipe and returned to first position, the face plate not being rotated on the return trip. Shortly 100 after the carriage starts on its reverse movement the lever 42 is moved by the cam so that the latch 43 snaps into place to interlock the two levers 39 and 42, and on reaching the end of the recovery movement the friction clutch is once more released automatically. A new length of pipe is now 105 placed in the machine, the rear end mounted on the face plate chuck and the forward end coupled to the rear end of the preceding 110 length of pipe by suitable movement of the carriage without rotation of the pipe. The clutch gear 51 is now shifted by the lever 57 to engage the gear 67 and sleeve 60, and with the throwing in of the clutch 34, the wrapping movement of the pipe once more begins. Shortly after the forward movement 115 begins, movement of the lever 42 permits the latch 43 to snap into place to lock the levers 39 and 42 so that when the cam roller 48 reaches the offset portion 83 in the cam, 120 movement of the pipe automatically ceases to permit the wrapping to be interrupted over the coupling. At this point the wrapping is torn to leave the adjacent ends of the joined pipes bare. The end of the strip 125 is then started again by hand and the cycle of operations repeated.

I claim:

1. In a machine for wrapping objects, a

carriage, a track on which the carriage is movable, a chuck on the carriage for supporting one end of the object, means for propelling the carriage along the track, and 5 means for rotating the object.

2. In a machine for wrapping objects, a carriage, a track on which the carriage is movable, a chuck on the carriage for supporting one end of the object, means for propelling the carriage along the track, and 10 means for rotating the object, and means for adjusting to a predetermined ratio the rotary speed of the object and the speed of movement of the carriage.

15 3. In a machine for wrapping objects, a carriage, a track on which the carriage is movable, a chuck on the carriage for supporting one end of the object, means for propelling the carriage along the track, and 20 means for rotating the object, and means for feeding a strip of wrapping material to said object.

4. In a machine for wrapping objects, a carriage, a track on which the carriage is 25 movable, a chuck on the carriage for supporting one end of the object, means for propelling the carriage along the track, and means for rotating the object, a body of fluid and means for feeding a strip of 30 wrapping material thru said fluid to said object.

5. In a machine for wrapping objects, a carriage, a track on which the carriage is 35 movable, a chuck on the carriage for supporting one end of the object, means for propelling the carriage along the track, and means for rotating the object, means for feeding a strip of wrapping material to 40 said object, and means for supporting the other end of the object.

6. In a machine for wrapping objects, a carriage, a track on which the carriage is movable, a chuck on the carriage for supporting one end of the object, means for 45 propelling the carriage forwardly along the track, means for rotating the object, and means for effecting a recovery movement of said carriage.

7. In a machine for wrapping objects, a 50 carriage, a track on which the carriage is movable, a chuck on the carriage for supporting one end of the object, means for propelling the carriage along the track, means for rotating the chuck, and means 55 for adjusting to a predetermined ratio the rotary speed of the chuck and the speed of movement of the carriage.

8. In a machine for wrapping objects, a carriage, a track on which the carriage is 60 movable, a chuck on the carriage for supporting one end of the object, means for propelling the carriage along the track, means for rotating the chuck and means for 65 adjusting to a predetermined ratio the rotary speed of the chuck and the speed of

movement of the carriage, and means for feeding a strip of wrapping material to said object.

9. In a machine for wrapping objects, a carriage, a track on which the carriage is 70 movable, a chuck on the carriage for supporting one end of the object, means for propelling the carriage along the track, means for rotating the chuck, and means for adjusting to a predetermined ratio the rotary speed of the chuck and the speed of movement of the carriage, a body of fluid, and means for feeding a strip of wrapping material thru said fluid to said object.

10. In a machine for wrapping objects, a carriage, a track on which the carriage is movable, a chuck on the carriage for supporting one end of the object, means for propelling the carriage forwardly along the track, means for rotating the chuck, and means for adjusting to a predetermined ratio the rotary speed of the chuck, and the speed 85 of movement of the carriage, and means for effecting a recovery movement of said carriage.

11. In a machine for wrapping objects, a carriage, a track on which the carriage is movable, a chuck on the carriage for supporting one end of the object, a prime mover on said carriage, variable speed means for driving the chuck from the prime mover, means for propelling the carriage forwardly along the track, means for propelling the carriage backwardly along the track, and manually operated means for connecting the prime mover to either of said propelling means.

12. In a machine for wrapping objects a carriage, a track on which the carriage is movable, a chuck on the carriage for supporting one end of the object, a fixed rack, a driving gear on the carriage and meshing with the rack, a prime mover on the carriage, and means for operatively connecting and disconnecting the prime mover with the chuck and the driving gear.

13. In a machine for wrapping objects, a carriage, a track on which the carriage is movable, a chuck on the carriage for supporting one end of the object, a fixed rack, a driving gear on the carriage and meshing with the rack, a prime mover on the carriage, toothed clutch means interposed between the prime mover and the driving gear and the chuck, and a friction clutch interposed between the prime mover and the toothed clutch means.

14. In a machine for wrapping objects a carriage, a track on which the carriage is movable, a chuck on the carriage for supporting one end of the object, a fixed rack, a driving gear on the carriage and meshing with the rack, a prime mover on the carriage, means operatively connecting the prime mover with the chuck and the driv-

- ing gear, and automatically operating means for disconnecting the prime mover from the chuck and driving gear at predetermined points during the movement of the carriage.
15. In a machine for wrapping objects a carriage, a track on which the carriage is movable, a chuck on the carriage for supporting one end of the object, a fixed rack, a driving gear on the carriage and meshing with the rack, a prime mover on the carriage, clutch means interposed between the prime mover and the driving gear and the chuck, manually operated means for closing and opening the clutch and automatically operated means for opening the clutch.
16. In a machine for wrapping objects a carriage, a track on which the carriage is movable, a chuck on the carriage for supporting one end of the object, a fixed rack, a driving gear on the carriage and meshing with the rack, a prime mover on the carriage, connecting means including a clutch between the prime mover and the driving gear, connecting means including a clutch and speed varying mechanism between the prime mover and the chuck, and manually controlled means for operating the clutches.
17. In a machine for wrapping objects, a carriage, a track on which the carriage is movable, a chuck on the carriage for supporting one end of the object, a source of power, and selective means for connecting said power source to drive the carriage and the chuck together or separately.
18. In a machine for wrapping objects, a carriage, a track on which the carriage is movable, a chuck on the carriage for supporting one end of the object, a source of power, and selective means for connecting said power source to drive the carriage forwardly and simultaneously rotate the chuck or to drive the carriage backwardly or rotate the chuck.
19. In a machine for wrapping objects, a carriage, a track on which the carriage is movable, a chuck on the carriage for supporting one end of the object, a prime mover on the carriage, means adapted to be driven by the prime mover for propelling the carriage along the track, means adapted to be driven by the prime mover for rotating the chuck and selective means for connecting the prime mover to either or both of said driven means.
20. In a machine for wrapping objects, a carriage, a track on which the carriage is movable, a chuck on the carriage for supporting one end of the object, a prime mover on the carriage, means adapted to be driven by the prime mover for propelling the carriage along the track, means adapted to be driven by the prime mover for rotating the chuck, selective means for connecting the prime mover to either or both of said driven means, and means for varying the ratio of speeds of the driven means.

In testimony whereof, I have hereunto set my hand.

CHARLES S. EVANS.
